UNITED STATES PATENT OFFICE

LAURENCE WILLIAMS, OF SYRACUSE, NEW YORK

DESIGN FOR A COMBINED CLOCK AND LAMP STAND

Application filed November 9, 1931. Serial No. 41,664. Term of patent 7 years.

To all whom it may concern:

Be it known that I, LAURENCE WILLIAMS, a citizen of the United States, residing in the city of Syracuse, in the county of Onondaga and State of New York, have invented a new, original, and ornamental Design for Combined Clock and Lamp Stand, of which the following is a specification, reference being had to the accompanying drawings, forming part thereof.

Figure 1 is a perspective view of my combined clock and lamp stand.

Figure 2 is a top plan view of the device shown in Figure 1.

I claim:

The ornamental design for a combined clock and lamp stand substantially as shown.

LAURENCE WILLIAMS.
